CLAIM

The ornamental design for a clip for cabinet door drying rack, as shown and described.

DESCRIPTION

FIG. 1 is a front perspective view of a clip for cabinet door drying rack showing my new design;
FIG. 2 is a front elevation view thereof;
FIG. 3 is a rear elevation view thereof;
FIG. 4 is a bottom plan view thereof;
FIG. 5 is a top plan view thereof;
FIG. 6 is a left side elevation view thereof;
FIG. 7 is a right side elevation view thereof; and,
FIG. 8 shows the clip for cabinet door drying rack of FIG. 1 in use.

The broken lines in the drawings showing the cabinet doors, enlarged view of the clip, and a cabinet door drying rack in FIG. 8 form no part of the claimed design.

The dash-dot lines illustrate the boundary of the enlarged views and form no part of the claimed design.
